(57) **CLAIM**

We claim the ornamental design for a handheld dual grater/zester, as shown and described.

DESCRIPTION

FIG. 1 is a perspective view of the handheld dual grater/zester with cap;

FIG. 2 is front view of the design embodiment shown in FIG. 1;

FIG. 3 is a back view of the design embodiment shown in FIG. 1;

FIG. 4 is a bottom side view of the design embodiment shown in FIG. 1;

FIG. 5 is a top side view of the design embodiment shown in FIG. 1; and,

FIG. 6 is a bottom side view of the design embodiment shown in FIG. 1 without cap.

The subject matter shown in dashed lines, and any surfaces of the design not shown, including interior surfaces, form no part of the claimed invention.
